Robert Woodlape Graham

UNITED STATES PATENT OFFICE.

NELSON WOODTHORPE GRAHAM, OF JOHANNESBURG, TRANSVAAL, SOUTH AFRICA.

WRENCH.

1,422,563.

Specification of Letters Patent. Patented July 11, 1922.

Application filed September 15, 1920. Serial No. 410,556.

To all whom it may concern:

Be it known that I, NELSON WOODTHORPE GRAHAM, a subject of the King of Great Britain, and resident of Johannesburg, 5 Transvaal Province, Union of South Africa, have invented certain new and useful Improvements in Wrenches, of which the following is a specification.

This invention consists of improvements 10 in wrenches and especially that type of wrench which is provided with serrated or roughened jaws and is chiefly used to screw up or unscrew pipes, cylindrical rods and the like. The invention may be adapted with 15 equal facility to new wrenches, or to old wrenches of the type referred to in which the screw or nut, usually provided, or either of them, are worn out or broken.

The objects of my invention are to provide 20 a cheap and strong wrench, when the invention is applied to a new wrench, and to enable old wrenches, the screws or nuts of which have been stripped or broken, (and which otherwise would be discarded 25 or require to be provided with a new jaw) to be repaired and re-used.

In the accompanying drawings I illustrate 30 a wrench embodying the invention in the preferred form,

Fig. 1 being a side elevation of the tool, and

Fig. 2 a view at right angles to Fig. 1.

The drawing illustrates the preferred form of the invention when embodied in the 35 construction of a new wrench. In this construction a handle 1, similar to the usual handle portion of ordinary wrenches, is provided and is formed with or has affixed to it at its one extremity, the fixed jaw 2 of the 40 wrench. 3 is the member or part which, in the case of an ordinary wrench, rotatably carries the adjusting nut for the movable jaw. The part or member 3 is hinged or pivoted 45 at 4 to the handle portion 1 underneath the jaw 2, as is usual, and it has an extension 5 which loosely embraces the handle portion 1, as indicated at 6. 7 is the ordinary spring which at one end is attached to the handle 1 and at the other end engages with the 50 extension 5 and serves through said extension 5, at the one side of the handle, resiliently to hold the part 3 in place. 8 is the ordinary spring which is fixed at the one end to the other side of the handle and at its other end 55 engages with the part 3 and serves, at the

other side of the handle, resiliently to hold the part 3 in place.

9 is the other and adjustable jaw which is shown constructed integral with an extension or part 10, which, in the case of an ordinary wrench, is the part which is screw-threaded to engage with the adjusting nut. In my construction both screw-thread and nut are dispensed with, and consequently the sides of the part 3 do not require to be 65 provided with the slots for the nut. As in existing wrenches, the member or part 3 is hollow or has an opening 11 through which the extension or part 10 passes, and in which it is adapted to move up and down 70 in adjusting the distance between the jaws, as required.

For the purpose of adjusting the movable jaw 9 relative to the fixed jaw 2, the extension 10 of the former is provided with one 75 or a plurality of rows of holes 12, which, as shown, are equally spaced apart in all of the rows. In the drawing it is shown provided with two parallel rows of such holes, those of the one row being staggered in relation 80 to those of the other, and the distance between the holes of each row being the same. By providing two or more rows of holes 12, and staggering the same, as shown, it ensures a finer adjustment of the relative positions of the jaws 2, 9.

13, 14, 15, 16, are four holes formed through both sides of the part 3, which are adapted to coincide with the holes 12 in different positions of the jaw 9. The distance 90 between the two holes 13, 15, which are adapted to coincide with the one row of holes, 12 is one and one half times the distance between the holes 12 of each row, and the other two holes 14, 16, which are adapted 95 to coincide with the other row of holes 12, are also positioned one and one half times the distance between the holes 12 of each row. The hole 14 is positioned in advance of the hole 13, in the direction of the rows 100 of holes 12, by a distance equal to one quarter of the distance between the holes 12 of each row. In like manner the hole 16 is in advance of the hole 15 by a distance equal to one quarter of the distance between the holes 105 12 of each row. As will be understood on reference to the drawing, by providing the two rows of holes 12, and positioning the holes 13, 14, 15, 16, as shown and described, the distance between the jaws 9, 2, can be 110

varied by a distance equal to one quarter the distance between the holes 12 of each row.

In order to retain the jaw 9 in any desired position I provide a pin 17 which is preferably attached by means of a chain 18 to the end of the extension 10. The pin 17 is adapted to pass through any of the holes 13, 14, 15, 16, and any one of the holes 12, which may coincide with any one of said holes 13, 14, 15, 16, as is clearly shown in the drawing.

In adapting the invention to old wrenches, the nut will be discarded and the screw-threaded extension of the loose jaw may have one or more rows of the holes 12 drilled through it and disposed in a longitudinal direction. The pin will be attached to the end of the extension. To secure the loose jaw in any adjusted position, by limiting its movement in an outward direction, the pin will pass through the slots provided for the nut in the sides of the part 3 and engage in one of the holes in the extension. In such construction the pin will engage with the top of the slot or that side nearest the jaws and so operate to prevent further opening thereof.

What I claim as my invention and desire to protect by Letters Patent is:—

- 30 1. A wrench comprising a handle portion provided with a fixed jaw, and a movable jaw, the latter having an extension in which a row of holes is formed in the direction of its length, a part pivotally connected to the fixed jaw and having an opening through which the movable jaw extension passes and moves in a direction parallel to the handle portion, and also having a hole which passes through the sides thereof and communicates with said opening, and a pin which is adapted to engage in said hole and also in any one of the row of holes in the movable jaw extension to retain the movable jaw in different positions relative to the fixed jaw.
- 45 2. A wrench comprising a handle portion provided with a fixed jaw, and a movable jaw, the latter having an extension in which a plurality of rows of holes are formed in the direction of its length, a part pivotally connected to the fixed jaw and having an opening through which the movable jaw extension passes and moves in a direction par-

allel to the handle portion, and also having a plurality of holes which pass through the sides thereof and communicate with said opening, and a pin which is adapted to engage in any one of said last-mentioned holes and also in any one of the holes in the movable jaw extension to retain the movable jaw in different positions relative to the fixed jaw.

3. A wrench comprising a handle portion provided with a fixed jaw, and a movable jaw, the latter having an extension in which a plurality of rows of holes are formed in the direction of its length and are staggered in adjacent rows, a part pivotally connected to the fixed jaw and having an opening through which the movable jaw extension passes and also having a plurality of holes which pass through the sides thereof and communicate with said opening, certain of said holes being adapted to be placed in coincidence with the holes of each row of holes in the movable jaw extension, and a pin which is adapted to engage in any one of the holes in the part connected to the fixed jaw and also in any one of the holes in the movable jaw extension to retain the movable jaw in different positions relative to the fixed jaw.

4. A wrench comprising a handle portion provided with a jaw, a movable jaw constructed with an extension having a plurality of rows of holes, which are staggered in adjacent rows, a part pivotally attached to the handle and having an opening through which the extension of the movable jaw passes and a plurality of rows of staggered holes arranged in the direction of the holes of each row of holes in the movable jaw extension, and a pin which is adapted to engage in any one of said staggered holes and also in any one of the rows of holes in the movable jaw extension to retain the movable jaw in different positions relative to the fixed jaw.

In testimony whereof I have signed my name to this specification in the presence of two subscribing witnesses.

NELSON WOODTHORPE GRAHAM.
